UNITED STATES PATENT OFFICE.

CHARLES W. KECKLER, OF NEWARK, NEW JERSEY, ASSIGNOR, BY MESNE ASSIGNMENTS, TO WESTERN ELECTRIC COMPANY, INCORPORATED, A CORPORATION OF NEW YORK.

TELEPHONE SYSTEM.

1,251,536.

Specification of Letters Patent.

Patented Jan. 1, 1918.

Application filed November 16, 1915. Serial No. 61,744.

To all whom it may concern:

Be it known that I, CHARLES W. KECKLER, a citizen of the United States, residing at Newark, in the county of Essex and State 5 of New Jersey, have invented certain new and useful Improvements in Telephone Systems, of which the following is a full, clear, concise, and exact description.

This invention relates to telephone systems, and more particularly to house or intercommunicating systems.

The object of this invention is to provide improved means for rendering secret telephone service, that is, to prevent other stations of a telephone system interfering with or overhearing a conversation carried on between two connected stations or a conversation carried on over a trunk circuit extending between the intercommunicating 20 system and another telephone system exterior thereto.

One feature of this invention is to provide improved means for preventing other stations of a telephone system intercepting a 25 call or interfering with the operations by which one station calls and establishes a connection with another station or with a trunk circuit.

Another feature of this invention is to 30 effectively continue the secret service condition of a connection until the receiver at each one of two connected stations has been returned to its switchhook.

Another feature of this invention is to 35 provide improved means for indicating to a calling station the busy or idle condition of a called station or trunk circuit, and to inform the calling party, irrespective of speaking, that the call has been answered.

A further feature of this invention is to 40 dispense with an attendant's station and to provide that trunk circuit connections may be handled and transferred from one station to another by any station in the system.

Still another feature of this invention is to 45 provide improved means whereby one station of a secret service intercommunicating system, having connection with an outside line, may bring in another intercommunicating station on the system, and all 50 three stations converse together without disturbing the secrecy thereof.

In accordance with the features of this invention, two relays are added to the usual

equipment, consisting of a telephone set, a 55 call signal and a plurality of switching keys at each station; and a plurality of relays, a repeating coil and two call signals are provided for each trunk circuit extending from the intercommunicating system to a 60 telephone exchange. These relays render all calling keys, call signals, except one of the signals associated with a trunk circuit, and switching keys normally disabled.

In this system, relay action takes place 65 after each manual operation in the processes of establishing a connection between two stations or between stations and a trunk circuit.

In originating a call, the first manual operation sets up relay action to exclude any other station which may seek connection with the calling station or with the trunk circuit when a call thereon originates at one of the intercommunicating stations. At the 70 intercommunicating stations this relay action also renders the calling position of the switching keys effective to initially set up a second relay action which results, first, in rendering the calling position of the 75 switching keys effective as ringing keys, second, to complete the circuits between the telephone set and the switching keys, third, to establish a locking circuit for the last relay operated, and fourth, to cause relay ac- 80 tion at the station called. The circuit changes, due to the operation of the relay at the latter station, first disable the circuit over which the second relay action at the 85 calling station took place, thereby guarding 90 the called station against another station which may attempt to secure a connection therewith and to render the calling signal effective to respond to the converted ring- 95 ing key at the calling station.

The switching keys are arranged to be locked by a common plate in an intermediate position at which certain contacts are effective to complete a connection for talking. A second non-locking position of the switching keys is present when the plunger of a key is fully depressed and renders other contacts effective to first complete a relay operating circuit and second to act as a ringing key.

In this system identical equipment is used at each station. Therefore, it will be understood that a description of the features

present at one station will apply to any one of the stations of the system.

This invention is illustrated diagrammatically in the accompanying drawing, in which two telephone stations, indicated as A and B, are shown in Figure 1, and in Fig. 2 similarly is shown the complete equipment for one end of a central-energy trunk circuit assumed to be connected with a telephone exchange system (not shown), all suitable for practising the features of this invention.

The characteristic operating and service features of the present invention may be described as follows: Referring to the drawing, the matter of service between stations local to the intercommunicating portion of the system will first be considered. A calling signal 23 and the calling-position contacts 31 of a switching key B¹ at station A are normally disabled at the separated contacts 12 of a relay 10, and a telephone set permanently connected with an associated pair of line conductors 15 and 16 is normally disconnected from the common or bus conductors 13 and 14 of the switching keys by the open position of the contacts 27 and 28 of the relay 25. In originating a call, the receiver is first removed from its switchhook, say at station A. Talking battery is thereupon supplied to the telephone set from the battery 1 through the two operating windings of the relay 10. The operation of this relay follows and renders the calling position of the switching keys effective, and the switching key B¹, associated with the line of the desired station, say the station B, is now fully depressed. The first impulse of current through the calling contacts 31 of the switching key B¹ initially operates the relay 25 at this station. This circuit is completed from the battery conductor 8, the contacts 12 of the relay 10, winding of the relay 25, contacts 31 of the key B¹, the line conductor 33, the contacts 43 of a relay 42 at station B, thence to the battery conductor 7. After being initially operated, the relay 25 is self-locked locally at station A on the battery 3 over a circuit from battery conductor 8, the contacts 12 of relay 10, the winding and contacts 26 of the relay 25 and contacts 17 of the switch-locking plate 18, to the battery conductor 7. The contacts 27 and 28 of the relay 25 and the contacts 29 and 30 of the switch key B¹ now include the telephone set at this station with the line conductors 33 and 34 respectively of the station B. In this position the left-hand winding of the relay 10 is connected in parallel over the line conductor 34 with the left-hand winding of the relay 42 at station B. The relay 42 is thereby operated and separation of its contacts 43 disconnects the circuit through which the

relay 25 at station A was initially operated, and the closing of the contacts 44 of the relay 42 prepares an operating circuit for the call signal 40. The closing of the contacts 26 of relay 25 at station A reverses the polarity of the calling battery 3 at the contacts 31 of the key B¹, thereby rendering this key effective to operate the signal 40 at station B. This signal operating circuit includes the battery conductor 7, contacts 17 of the key-locking bar 18, contacts 26 of the relay 25, contacts 31 of the key B¹, line conductor 33 to station B, thence over the switchhook contacts 36, the signal 40, contacts 44 of the relay 42 to the battery conductor 8. During the time the call bell 40 is active, the static or capacity balance of the telephone receiver circuits at station A change in unison with the operation of the contacts of the bell, and a corresponding tone is accordingly produced in the telephone receiver. This effect is possible for two reasons, first, that the signaling current is applied to the line conductor 33 without disconnecting this conductor from the telephone set at station A, and second, that the condenser effect at the telephone receiver is augmented, due to the left-hand winding of the relay 42 at station B now forming a path parallel with the left-hand winding of the relay 10 at station A, thereby diminishing the impedance between the telephone receiver and the capacity surface of the talking battery and circuits. The presence of this tone indication signifies to a calling party that the station wanted is idle, and conversely the absence of this tone indicates that the station wanted is busy. A further service advantage of the tone indication is that on cessation of tone, the calling party will know that the station called has answered.

The removal of the telephone receiver from its switchhook at station B, in response to the call, disconnects the signal bell 40 by the separation of the switchhook contacts 36, and the closing of contacts 37 and 38 of the switchhook completes a circuit through which talking current is supplied from the battery 1, over the right and left-hand windings of the relay 42 to the telephone set.

During the talking period, relays 10 and 25 at station A remain operated while only the relay 42 at the station B is energized, and so long as the receiver at either one of the connected stations is retained off the switchhook, the double wound relay at the station first to replace the receiver on the switchhook is retained by its left-hand winding, as this winding is then established in parallel with the left-hand winding of the corresponding relay at the other station. This action is reciprocal with respect to two connected stations, and is the same as the

corresponding operation already described in connection with the processes of making a call.

At the conclusion of a conversation, and when the telephone receiver at each station has been replaced on its switchhook, all of the relays are deenergized and the circuits restored to the normal condition. The restoring of the circuits to a normal condition, described in connection with the equipment at station A, is due, first, to the deenergizing of the relay 10 on cessation of talking current through the telephone set, and second, the separation of the contact 12 of this relay opens the locking circuit of the relay 25, which thereafter remains inert due to the separation of its contact 26 until reoperated by initiating a call to an idle station.

In order to describe the conditions which prevent other stations on the system interfering with or securing a connection with either one of two connected stations, let it be assumed that the station A is a third station and attempts to secure a connection with the station B while the latter station is busy. The relay 10 responds to the removal of the receiver from the switchhook at station A and the key B¹ is next fully depressed. The circuit through which the relay 25 now attempts to operate may be traced from the battery conductor 8, contacts 12 of the relay 10, winding of the relay 25, contacts 31 of the key B¹, line conductor 33 to the station B, thence to a point where this circuit stands open at the separated contacts 43 of the relay 42. Failure of the relay 25 to operate allows its contacts 27 and 28, respectively, to remain separated, and the telephone set at station A is thereby excluded from the line circuits of the station B.

From the foregoing description it will be evident that the separation of the contacts 43 of the relay 42 at the station B, and corresponding contacts of similar relays at other stations, constitute the means by which other stations are excluded during the time calling processes are in operation of being transmitted or received, as well as during the time two lines are connected for conversion.

A further operating feature of this system relates to an alternate method of restoring or deenergizing one of the relays at a station from which a previous successful call had originated. Let it be assumed that such a connection is now present at the station A,—the telephone receiver is retained off the switchhook after the first connection, and the relays 10 and 25 are accordingly energized. At this time let it also be assumed that the switching key B¹ is locked at the intermediate position by the engagement of its plunger shoulder with the locking bar 18. If, now, in attempting to secure con-

nexion with another station, without first replacing the receiver on the switchhook, another key (not shown) similar to key B¹ is depressed, the locking bar 18 will be mechanically moved to cause the contacts 17 to separate and thereby interrupt the locking circuit of the relay 25, permitting this relay to release. This feature renders it impossible for the relays 25 to first be operated over an idle line, and then by operating a key corresponding with another line on which a party may desire to listen, succeed in completing an irregular connection.

In describing the operations taking place when the trunk circuit C is used, the processes by which a station—say the station A—secures a connection with a subscriber whose line may be assumed as terminating in a telephone exchange (not shown) to which the trunk circuit C extends, will now be described.

The necessary manual operations at the station A correspond with those already described for a local call. The receiver is removed from the switchhook and a key C¹, corresponding with the trunk circuit C, is then fully depressed. The relay 10, now energized by the talking current through the telephone set, permits the key C¹ to complete a circuit from the battery conductor 8 of the calling battery 3, contacts 12 of the relay 10, winding of the relay 25, contacts 45 of the key C¹, a conductor 48, to the trunk circuit equipment, thence over the contacts 61 of a relay 60, the contacts 55 of a relay 54, to the battery conductor 7. The current impulse through the circuit just traced initially operates the relay 25 at station A, after which it is locked, as previously described. The telephone set is now connected through the contacts 27 and 28 of the relay 25, the bus conductors 13 and 14 and contacts 46 and 47, respectively, of the key C¹ in bridge on the trunk conductors 49 and 50. A branch circuit is thereby established from the conductor 5 of the battery 1, the winding of a relay 51, one winding of a repeating coil 75 to the conductor 49, thence through the telephone set at station A, returning over the conductor 50, a second winding of the repeating coil 75, to the conductor 4 of the battery 1. The operation of the relay 51 now effects the operation of a relay 54 and a relay 58 over the following circuits: conductor 8 of the battery 3, contacts 53 of the relay 51, the winding of the relay 54 to the conductor 6 of the battery 2, which is connected in accumulative series with the battery 3. The second circuit extends from the battery conductor 8, the contacts 53 of the relay 51, the left-hand winding of the relay 58 to the battery conductor 6. The separation of the contacts 55 of the relay 54 disconnects the battery

110

115

120

125

conductor 7, over which the relay 25 at station A was initially operated, and the contacts 56 of the relay 54 now complete a circuit for the signal 66. At the station 5 A the energized position of the relay 25 connects the neutral conductor 7 of the serially connected batteries 2 and 3 by way of the contacts 17 of the key-locking plate 18 to the contacts 45 of the key C¹, which is 10 continued fully depressed; thence, this circuit continues over the conductor 48 to the trunk circuit signal 66, the contacts 56 of the relay 54 to the battery conductor 8. The operation of this signal, which is of the 15 vibrating-interrupter type, sets up changes in the static or capacity balance of the circuit of the telephone receiver at the station A to produce a tone indication in the receiver. The signal 66 may be located at any point 20 where it may be desirable to keep a record of the outgoing trunk circuit calls. Although the contacts 59 of the relay 58 complete a circuit to establish a relay 60 in series with the main conductors of the trunk 25 circuit to the central-energy exchange (not shown), this relay does not operate, owing to the limited quantity of current permitted by the comparatively high resistance of a signal control relay at the exchange. This 30 signal relay, however, is operated to display a call signal at the exchange. On the call being answered at the exchange, the low resistance of the link circuit permits a sufficient quantity of current from the exchange 35 battery to operate the relay 60. The separation of the contacts 61 of the relay 60 disconnects the signal 66, and the calling party at station A may now release the key C¹ to its locking position and talk, by way 40 of the conductors 49 and 50 and the repeating coil 75, with the exchange. In the talking position the relays 10 and 25 at station A and the relays 51, 54, 58 and 60 of the trunk circuit C remain energized. 45 Telephone service of this character usually requires that the connection be retained at the exchange until a disconnect signal is received from the station of the intercommunicating system, and in the present system this takes place as follows: On disconnecting the telephone set from the bridged connection over the trunk conductors 49 and 50, by replacing the receiver on the switchhook at station A, the relay 51 is released, and this relay in turn releases the 55 relays 54 and 58. The separation of the contacts 59 of the relay 58 disconnects the relay 60, thereby causing a cessation of battery current over the line of the trunk circuit, 60 and accordingly a disconnect signal is displayed at the telephone exchange.

In unison with the releasing of the relay 51 of the trunk circuit, the telephone set at station A also disconnects the relay 10, 65 which in turn opens the locking circuit to

release the relay 25. Accordingly, all of the circuits are now restored to a normal or idle condition.

This system provides that any station may answer, and if necessary, transfer a trunk 70 circuit call to another station, thereby obviating the necessity of a so-called attendant station which is usually required for handling this service. The signal 70, connected in series with a condenser, thence in bridge 75 on the main line conductors of the trunk circuit responds to ringing current applied to the trunk circuit when a call originates at the exchange. The signal 70, or signals auxiliary thereto, may be so located that several of 80 the stations will receive the indication of an incoming trunk circuit call, thereby insuring that these calls will receive better attention.

In describing the processes by which an 85 incoming trunk call may be answered and transferred to another station, let it be assumed that in response to the operation of the signal 70 the call is answered by the station A, but the party wanted is at the 90 station B. At the station A the receiver is first removed from the switchhook and, secondly, the key C¹ is fully depressed, thereby energizing the relays 10 and 25 at station A, and the relays 51, 54, 58 and 60 of the trunk 95 circuit, all in the same manner and for the purposes already described in the matter of originating a trunk circuit call from the station A. At this time, however, the relay 60 receives sufficient current from the link circuit at the distant exchange to effect its operation immediately following the operation of the relay 58, and the contact 61 of the relay 60 disconnects the signal 66. The absence of tone in the receiver at station A, 100 otherwise set up by the signal 66 as described, indicates to the answering party that a connection is present on the trunk circuit at the exchange. The key C¹ may now be released to its intermediate locking position, and a conversation carried on over the 105 trunk circuit. On ascertaining that the call is for a party at the station B, a transfer key C² at the station A is momentarily depressed and completes a circuit from the 110 neutral battery conductor 7, the contacts 17 of the key-locking plate 18, contacts 26 of the relay 25, contacts 69 of the key C², conductor 71, the left-hand winding of the relay 67, the contacts 64 of the relay 63, to the 115 battery conductor 6. This momentary inclusion of the relay 67 on the battery 2 initially operates the relay 67, which is then self-locked on the series circuit formed of the batteries 2 and 3, over the following circuit: battery, conductor 6, contact 64 of the 120 relay 63, the right-hand winding and the contacts 68 of the relay 67, contacts 62 of the relay 60, the right-hand winding of the relay 58 to the battery conductor 8. At the 125 130

station A the telephone receiver is retained off the switchhook, and the key B¹, corresponding with the line conductors to station B, is fully depressed. In depressing the key B¹, a well-known action of the locking plate 18 releases the trunk circuit key C¹ and momentarily opens the contacts 17, thereby de-energizing the relay 25. On the restoring of the trunk key C¹ and the relay 25, the telephone set at station A is disconnected 5 from the trunk circuit conductors 49 and 50, thereby permitting the relay 51 to release, and in turn this relay releases the relay 54, the relay 58 remaining energized over the circuit just traced through its right-hand winding. If, now, the station B is idle, the relay 25 at station A will be operated, and a connection established between these stations, in a manner already described. On 10 the party at station B receiving the request to take up the trunk circuit call, the telephone receiver is retained off the switchhook and the key C¹ is depressed to the intermediate or locking position, and the transfer key C² is depressed momentarily. The key C² completes a circuit from the battery conductor 8, contacts 44 of the relay 42, the winding and contacts 39 of the relay 35, the contacts 41 of the key C², conductor 71, 15 the winding of the relay 63, contacts 52 of the relay 51, to the battery conductor 6, thereby operating the relay 35 at station B and the relay 63 of the trunk circuit. The relay 35 is rendered self-locked to include 20 the telephone set at this station with the bus conductors of the keys, thence over the respective contacts of the key C¹ to form a bridged circuit across the trunk conductors 49 and 50. The relay 51 is now operated 25 through the telephone set at station B and in turn effects the operation of the relay 54. Separation of the contacts 64 of the relay 63 disconnects the transfer relay 67, and in turn the separation of the contacts 52 of the 30 relay 51 disconnects the relay 63. The contacts 53 of the relay 51 reestablish the left-hand winding of the relay 58 on the batteries 2 and 3, by which the relay 58 is retained energized after the circuit through 35 its right-hand winding has been opened by the separation of the contact 68 of the relay 67. The relays 42 and 35 at station B, and the relays 51, 54, 58 and 60 of the trunk circuit, are now energized, and the circuits 40 are thereby conditioned to permit a conversation to be carried on from the station B over the trunk circuit C. At the conclusion of the conversation and when the receiver at station B is replaced on the switchhook, the 45 relay 60 is finally released to permit a disconnect signal to be displayed at the exchange, all in a manner similar to that already described for the disconnect operation from the station A.

60 From the foregoing description it will be

apparent that during the time a completed connection is present on the trunk circuit, the separated contacts 61 of the relay 60, in addition to the separated contacts 55 of the relay 54, disable the circuit of the conductor 70 48 through which it is necessary that the switching relay, as the relay 25 at station A, at another station must be initially operated in order to secure a connection with the trunk circuit. Therefore, during the 75 time a call is being transferred and the relay 54 accordingly deenergized, the contacts 61 of the relay 60 continue the disabled condition of the conductor 48 to render the trunk circuit inaccessible to other stations that may attempt to secure a connection therewith by use of the trunk circuit key C¹. The repeating coil 75 and the associated condensers of the trunk circuit C serve to prevent interference between the 80 85 different centralized current sources.

It will be understood that although a switching key may be retained fully depressed after a station or a trunk circuit call has been answered, this condition does 90 not prevent or materially affect the talking properties of the connection.

The present invention is also arranged so that in addition to any station being able to answer a trunk call and to directly transfer such call to another station, it is also possible for any station in connection with the outside trunk to bring in another station and for all the parties so connected to converse together. By requiring a definite act on the 95 part of the station in connection with the trunk line to bring in the second station, and a definite act by the party at the second station on answering, the secrecy of the system is preserved.

Let us assume that the party at station A is in connection with an outside party through the trunk line and desires to include station B in the conversation. The party at station A would press his transfer key C² 100 momentarily to hold the trunk line. The key B' is next depressed to signal station B. On the party at station B answering, he would be informed that his presence was desired 105 in a conversation between stations A, B and the outside trunk line. B would thereupon press his trunk button C' to intermediate position, and then depress his key button C², thereby connecting his telephone set to the 110 trunk line. The operation to this point is 115 identical with the transfer of a trunk call from station A to station B. The party at station A, however, is to take part in the conversation so he will not hang up his receiver at this time, but retain his connection 120 with B; this connection extending from line 33, secured to the hook at station B, over this line to station A, contact 29, outer right-hand armature and front contact 27 of relay 125 25, conductor 15, hook receiver and transmit- 130

ter of station A, line 16, inner right-hand armature and front contact 28 of relay 25, contact 30, conductor 34 of station A, to line 34 of station B, which line extends from the 5 transmitter and receiver of station B. Station A is thus placed in parallel with station B, and thus secures telephonic communication with the outside party over the trunk connection established with station B in the 10 operation previously outlined.

Inasmuch as the connection for the outside trunk is now made at station B, the party at station A can withdraw from the conversation and hang up his receiver at any time 15 without destroying the connection existing between station B and the outside party. As soon as the receiver is replaced at station A, the relay 10 falls off, resulting in the de-energization of relay 25, so that station A 20 cannot again secure connection with station B or the trunk line while they remain busy, although station A is free to call idle stations in the usual manner. If, after station A has withdrawn from the conversation, the 25 party at station B should desire to bring another station into the conversation, the operation previously described would be repeated for the desired station.

What is claimed is:

30 1. In a telephone system, a plurality of line circuits, a telephone set associated with each line circuit, relays for each line circuit, centralized sources of current for said telephone system, and manually operated switching means for each line circuit adapted to control and coöperate with relay action on each one of two line circuits in completing a connection therebetween.

40 2. In a telephone system, a plurality of line circuits, a telephone set associated with each line circuit, relays for each line circuit, centralized sources of current for said telephone system, manually operated switching means for each line circuit adapted to coöperate with said relays in completing a connection between two line circuits, and means operated by said relays to automatically alter the circuit connections of a line in order that the line will be accessible when 45 idle and non-accessible when busy to other lines which may attempt to secure a connection therewith.

50 3. In a telephone system, a plurality of line circuits, a telephone set associated with each line circuit, relays for each line circuit, centralized sources of current for said telephone system, manually operated calling means for each line circuit, and means operated by said relays for normally disabling 55 said manually operated calling means.

60 4. In a telephone system, a plurality of line circuits, a telephone set associated with each line circuit, relays for each line circuit, a battery current signal for each 65 line circuit, centralized sources of current

for said telephone system, and means operated by said relays to normally disable said signals.

5. In a telephone system, a plurality of line circuits, a telephone set associated with each line circuit, relays for each line circuit, normally disabled calling means for each line circuit, centralized sources of current for said telephone system, means operated by the telephone set of a calling line to set 75 up relay action thereon, and means controlled by said relay action to render said calling means effective to seize an idle line circuit for use.

6. In a telephone system, a plurality of line circuits, a telephone set associated with each line circuit, relays for each line circuit, a battery current signal for each line circuit, calling means for each line circuit, centralized sources of current for said telephone 85 system, and means controlled by said relays during the calling processes to permit said calling means to first seize an idle line by setting up relay action thereon and second to condition said calling means to operate 90 the signal associated with the line circuit seized.

7. In a telephone system, a plurality of line circuits, a telephone set for each line circuit, a battery current signal for each 95 line circuit, relays for each line circuit, centralized sources of current for said telephone system, manually operated calling means for each line circuit adapted to coöperate with said relays in operating said signals, and means associated with said calling means co-operating with means associated with said relays to condition the signal of a called line to produce a tone indication in the telephone receiver of the calling line. 100

8. In a telephone system, a plurality of line circuits, a telephone set associated with each line circuit, relays for each line circuit, centralized sources of current for said telephone system, switching keys for each line 110 circuit adapted to coöperate with action of said relays on each one of two lines in completing a connection therebetween, locking means operated by the keys for retaining said keys in an effective position, and circuit controlling contacts operated by said locking means to retain one of said relays energized during the time a connection is 115 continued between two line circuits.

9. In a telephone system, a plurality of line circuits, a telephone set comprising a transmitter, receiver and hook switch associated with each line circuit, centralized sources of current for said telephone system, circuit connections individual to each 120 of said sets through which each of said sets is connected to other line circuits seeking connection therewith, and means operated by removal of the telephone receiver of a set from its hook in initiating a call to open the 125 130

- circuit connection individual thereto to prevent connection with said telephone set by other line circuits seeking connection therewith.
- 5 10. In a telephone system, a plurality of line circuits, a telephone set comprising a transmitter, receiver and hook switch associated with each line circuit, centralized sources of current for said telephone system, circuit connections individual to each of said line circuits through which each of said line circuits is connected to other line circuits seeking connection therewith, and means operated by removal of the telephone receiver of a set from its hook in initiating a call to open the circuit connection individual to the line circuit associated therewith to protect such line circuit from seizure by other line circuits.
- 10 11. In a telephone system, a plurality of line circuits, a telephone set comprising a transmitter, receiver and hook switch associated with each line circuit, centralized sources of current for said telephone system, circuit connections individual to each of said line circuits through which each of said line circuits is connected to other line circuits seeking connection therewith, and a relay for each line circuit operated by removal of the telephone receiver of a set from its hook in initiating a call to open the circuit connection individual to the line circuit associated therewith to protect such line circuit from seizure by other line circuits.
- 15 12. In a telephone system, a plurality of line circuits, a telephone set associated with each line circuit, centralized sources of current for said telephone system, circuit connections individual to each of said line circuits through which other line circuits seeking connection with such individual line circuit obtain connection therewith, manually operated switching means for each line circuit, and means operated immediately upon the actuation of said switching means to interrupt the circuit connection individual to the particular line circuit called to protect such particular line circuit from seizure by other of said other line circuits.
- 20 13. In a telephone system, a plurality of line circuits composed of two conductors only, a telephone set associated with each line circuit, a plurality of relays for each line circuit, centralized sources of current for said telephone system, test circuits for each of said line circuits extending over one of the line wires of the respective line circuit and conditioned by the operation of one of the relays of the respective line circuit called, another of said plurality of relays of each of said line circuits controlling the association of a calling line circuit with a called line circuit and included in said test circuit, and manually-operated switching means for each line circuit governing the first mentioned of said plurality of relays of its respective line circuit to condition said test circuit.
- 25 14. In a telephone system, a plurality of local lines, a telephone set associated with each local line, a trunk line, means at each telephone set to effect connection with said trunk line, means to render a telephone set obtaining connection with said trunk line inaccessible to other lines, means for each of said telephone sets to secure connection with other of said sets, means to seize said other sets and render them inaccessible to other than the calling set, means whereby a trunk connection may be transferred from a telephone set connected with the trunk line to another set selected by the set first connected with the trunk line, and means whereby the trunk line is positively held against seizure by sets other than the one selected.
- 30 15. In a telephone system, a plurality of local lines, a telephone set associated with each local line, a trunk line, means at each set to effect connection with said trunk line, means to render a set obtaining connection with the trunk line free from seizure by other lines, means for each of said telephone sets to secure connection with other of said telephone sets, means to seize said other sets and render them inaccessible to lines other than the calling line, and means to secure mutual telephonic connection between said trunk line and the telephone sets of a plurality of said local lines.
- 35 16. In a telephone system, a plurality of local lines, a telephone set associated with each local line, a trunk line, means at each set to effect connection with said trunk line, means to render a set obtaining connection with said trunk line free from seizure by other lines, means for each of said telephone sets to secure connection with other of said telephone sets, means to seize said other sets and render them inaccessible to lines other than the calling line, means to bring the telephone set of another local line into telephonic connection with the set of a local line connected to said trunk line, and means to connect the telephone set of said other local line telephonically with said trunk line to establish a mutual telephonic connection between said trunk line and the telephone sets of the connected local lines.
- 40 17. In a telephone system, a plurality of local lines, a telephone set associated with each local line, a trunk line, means at each set to effect connection with said trunk line, means to render a set obtaining connection with said trunk line free from seizure by other lines, means for each of said telephone sets to secure connection with other of said telephone sets, means to seize said other sets and render them inaccessible to lines other than the calling line, means to bring the

telephone set of another local line into telephonic connection with the set of a local line connected to said trunk line, means to connect the telephone set of said other local line 5 telephonically with said trunk line to establish a mutual telephonic connection between said trunk line and the telephone sets of the connected local lines, and means to enable the telephone set of one of said connected

local lines being disconnected without disturbing the telephonic connection between the trunk line and the other of said local lines connected thereto. 10

In witness whereof I hereunto subscribe my name this 13th day of November, A. D. 15 1915.

CHARLES W. KECKLER.
